UNITED STATES PATENT OFFICE

JAMES E. BURNS, OF BRIDGEPORT, CONNECTICUT, ASSIGNOR TO REMINGTON ARMS COMPANY, INC., A CORPORATION OF DELAWARE

PRIMING MIXTURE

No Drawing.

Application filed September 26, 1928. Serial No. 309,129.

This invention relates to priming mixtures for ammunition, particularly priming mixtures of the "non-corrosive" type, such mixtures not only leaving no corrosive residue in the bore of the gun but apparently actually coating the bore of the gun with an adherent protective film which prevents the formation of rust even under the most adverse conditions.

10 It has long been recognized that potassium chlorate, the most commonly used oxidizer in priming mixtures, was responsible for the corrosion of gun barrels which occurred subsequent to firing even though the barrel had 15 been carefully cleaned and oiled. Potassium chlorate however, by reason of its high oxygen content, the ease with which it releases its oxygen when heated and its stability in the presence of moisture was remarkably well adapted for use as a priming mixture oxidizer, and the securing of a substitute therefor was a problem of great difficulty. 20 Many non-corrosive priming compositions have been tried but very few of these have 25 been sufficiently successful to be actually embodied in a manufacturer's commercial product.

Recently, however, carefully prepared and proportioned compositions, using barium nitrate as an oxidizer have been marketed with extraordinary success. In these compositions the content of mercury fulminate is comparatively high on account of the necessity for reaching the high temperature at which barium nitrate yields its oxygen. Priming mixtures containing a large amount of mercury fulminate are undesirable for several reasons. Mercury fulminate is comparatively expensive and the cost of the mixture is 40 increased with an increase in the fulminate content. Of greater importance, however, is the fact that mercury fulminate is of a poisonous nature and the preparation and handling of mixtures containing a great deal 45 of fulminate are difficult and may be in-

jurious to the workmen. Mercury fulminate is moreover, highly explosive, and must always be handled with extreme care.

The present invention comprises the discovery of an explosive which may be substituted for a part of the mercury fulminate in non-corrosive mixtures. The fulminate content being thus reduced, the mixture is cheapened and becomes much more safe to make and handle. For this purpose lead 50 trinitroresorcinate, the normal lead salt of styphnic acid (trinitroresorcinol) has been found to be most desirable. The replacement of a part of the mercury fulminate by lead trinitroresorcinate not only makes the mixture more suitable for handling and loading 55 but also serves to regulate the combustion of the mixture in such a way as to eliminate certain irregularities which appear to be inevitable in non-corrosive mixtures containing 60 mercury fulminate only as an explosive.

Mercury fulminate detonates under the impact of the firing pin but this action being an instantaneous detonation, and not combustion, does not produce a sustained flame. 70 The result is that the temperature may not be raised sufficiently to effect the proper reaction between the fuel and the sluggish non-corrosive oxidizer. Increasing the fulminate content merely serves to increase the force 75 of this detonation, and not to appreciably increase the duration of the accompanying flame, and furthermore the increase in the fulminate content is productive of pierced and broken cartridge heads due to the excessive momentary pressure brought about 80 by the detonation. It has been found accordingly, that non-corrosive primers which depend on mercury fulminate alone as a combustion initiator are subject to certain 85 irregularities of performance even when most carefully proportioned and mixed and loaded with the utmost care. These variations, while not of sufficient magnitude to 90 destroy the usefulness of the mixture are

nevertheless undesirable and place certain restrictions upon the range of usefulness of such mixtures.

Lead trinitroresorcinate is less sensitive to blow and shock than mercury fulminate but its reaction time is much longer, and is accompanied by well sustained flame. This may be due to the fact that the decomposition of lead trinitroresorcinate results in much more free carbon than the decomposition of mercury fulminate. This carbon is burned with oxygen supplied by the priming mixture oxidizer with a hot and well sustained flame. Furthermore, the presence of the excess of nascent carbon serves to accelerate the release of oxygen by the otherwise sluggish barium nitrate, and the accompanying heat raises the temperature to the point where oxygen is liberated for the combustion of the fuel. One formula which has given excellent results is the following:

	Per cent
Mercury fulminate	30
Lead trinitroresorcinate	10
25 Barium nitrate	29
Lead sulphocyanate	10
Abrasive	20
Binder	1

30 These proportions, however, may be substantially varied. Good results have been secured with mixtures containing as little as 5% or as much as 20% of lead trinitroresorcinate, the mercury fulminate content being varied accordingly, as between the range of 20% and 40%. For example, the following is a very successful formula:

	Per cent
Mercury fulminate	31.5
40 Lead trinitroresorcinate	5.5
Barium nitrate	30.5
Lead sulphocyanate	10.5
Abrasive	21
45 Binder	1

50 The mixtures of this invention are especially adapted for rim fire cartridges, into which they are loaded in a moist condition. A pellet of the moist priming mixture is dropped into the shell, and spun out into the shell rim by a spinning punch. The shell or powder case is comparatively short, and the powder lies in immediate contact with 55 the priming mixture. Such rim fire cartridges require a priming mixture differing somewhat from that used for center fire cartridges in which the mixture may be loaded dry and is placed in a separate cup which communicates with the end of a long powder case through a flash hole. The present invention is thought to constitute the first rim fire mixture containing mercury fulminate and lead trinitroresorcinate, and the appended claims are to be broadly construed.

What is claimed is:

A noncorrosive priming mixture for wet loading into rim fire cartridges having substantially the following composition:

	Approximate per cent
Mercury fulminate	30
Lead trinitroresorcinate	10
Barium nitrate	29
Lead sulphocyanate	10
Abrasive	20
Binder	1
